UNITED STATES PATENT OFFICE.

WILLIAM SCHILLING, OF CONSHOHOCKEN, PENNSYLVANIA

BOAT-PUSHER HEAD.

No. 910,090.

Specification of Letters Patent. Patented Jan. 19, 1909

Application filed August 1, 1908. Serial No. 446,385.

To all whom it may concern:

Be it known that I, WILLIAM SCHILLING, a citizen of the United States, residing at Conshohocken, in the county of Montgomery and State of Pennsylvania, have invented certain new and useful Improvements in Boat-Pusher Heads, of which the following is a specification.

My invention relates to means for poling or pushing boats over flats or shallows such as are used by gunners and under like circumstances, and particularly it relates to a head to be attached to the pushing pole, the object of the invention being to provide a pushing pole head having such a shape and contour as shall especially fit it for the work to be done, which shall provide an extended surface for bearing against the mud of the river bottom, of such contour that it will have a more or less extended contact with the ground or mud, in all positions of the pole and which will permit the pushing head to be readily detached from engagement with the mud in case it is forced into the mud too far.

The invention consists broadly in a pusher having at its end a globular head which is so attached to the pole that it is readily removable therefrom, or replaceable upon another pole.

In the drawings Figure 1, is a side elevation of a pusher head and part of a pole constructed in accordance with my invention. Fig. 2, is a longitudinal section thereof showing the preferred attachment of the head to the pole.

In the drawings A designates a boat pushing pole of any desired form or length, B designates a cylindrical ferrule capable of receiving the lower end of the pole, the extremity of said ferrule being formed with a hemispherical socket C. Fastened within the socket C is a solid ball D of sufficient weight to keep the end of the pole downward and prevent any tendency on the part of the pole to float upward. While the head C should be heavy enough, at the same time it should not be so heavy as to add to the work of poling.

Preferably the ferrule is formed of sheet metal bent into a cylinder, with the hemispherical socket C thereon. The socket C is brazed or soldered on the upper end of the ferrule. The spherical head D may be formed of any suitable material, but preferably of wood, and fits within the hemi-

spherical socket, and is fastened therein by means of cement, white lead, plaster, or any other suitable material of such character that it will hold the head solidly in place, 60 and not be softened by the water.

While I have described the socket C as formed separately from the ferrule B, I do not wish to be limited thereto as the socket might be attached to or formed with the ferrule in any suitable manner. Openings are made in the ferrule into which screws 65 may be inserted whereby the head may be attached to the pushing pole.

It will be seen that no matter at what 70 angle the pushing pole is held the globular head will always have a good bearing surface; and that at the same time it is so enlarged that the pole can be pushed into the mud or ground, and hence there will be no 75 pull required in order to release the pole. With ordinary poles shod with a device which penetrates the ground there is almost always a jerk required in order to free the pole from the mud. This jerk is very liable 80 to occur at an inopportune moment as when the gunner in the bow of the boat is about to fire. This of course, destroys his aim and causes him to miss.

With my device there is no jerk, the pole 85 may be easily detached from engagement with the surface of the mud, it may easily slip along the surface of the mud, and has a good contact with the surface no matter at 90 what angle the pole is held, or what the 95 contour of the bottom of the stream. If the pole is broken the device can be readily attached to another pole, or it may be removed from the pole, when the necessity for its use has expired.

Another point of advantage is that the globular contour of the head permits it to be easily withdrawn in case by any chance it should be submerged in the mud. The globular contour prevents it sticking and 100 also presents in all positions of the pole a surface without an edge and hence with no liability to sink into the mud.

Having thus described my invention what I claim as new and desire to secure by Letters Patent is:

1. A pushing pole for boats comprising a rod or pole, a spherical head and a hemispherical socket secured to the pole, and the head secured in said socket.
2. A head for the pushing poles of boats comprising a ferrule adapted to receive the

pole, a socket and a head secured within said socket.

3. A head for pushing poles of boats comprising a cylindrical ferrule and hemispherical socket formed at the end thereof and a solid spherical head held within said socket.

4. A pushing pole for boats comprising a cylindrical ferrule adapted to receive a pole having at the end thereof a hemispherical socket, a solid ball within said socket and cement material between the ball and the socket.

5. A head for the pushing poles of boats

comprising a ferrule having a hemispherical socket at one end, said socket having a bead 15 formed on its edge, and a wooden ball inserted within said hemispherical socket and cemented thereto.

In testimony whereof I have signed my name to this specification in the presence of 20 two subscribing witnesses.

WILLIAM SCHILLING.
